United States Patent Office

Des. 217,504
Patented May 5, 1970

217,504

STRINGED MUSICAL INSTRUMENT SPECIFI-
CALLY, A UKRAINIAN VERTICAL HUSLI
(WINGED TYPE PSALTERY OR PROTO-
BANDURA)

Walter J. Pelensky, 19C Manheim Gardens,
Philadelphia, Pa. 19144

Original design application Mar. 28, 1968, Ser. No.
11,174. Divided and this application June 3, 1969,
Ser. No. 18,281

Term of patent 14 years

Int. Cl. D17—03

U.S. Cl. D56—1

Fig. 1

Fig. 4

Fig. 2

Fig. 3

FIG. 1 is a perspective view of a stringed musical instrument, specifically, a Ukrainian vertical husli (winged type psaltery or proto-bandura), according to my new design;

FIG. 2 is a front elevation or face view;

FIG. 3 is a left side elevational view;

FIG. 4 is a top plan view.

Portions of the drawings are shaded to indicate contrast.

This application is a division of my copending application, Ser. No. D-11,174, filed Mar. 28, 1968.

I claim:

The ornamental design for a stringed musical instrument specifically, a Ukrainian vertical husli (winged type psaltery or proto-bandura), as shown and described.
